UNITED STATES PATENT OFFICE.

CHRISTOPHER RICHARDSON, OF NEWARK, NEW JERSEY.

DESIGN FOR A CARVING-FORK.

SPECIFICATION forming part of Design No. 28,445, dated April 5, 1898.

Application filed October 6, 1897. Serial No. 654,301. Term of patent 14 years.

To all whom it may concern:

Be it known that I, CHRISTOPHER RICHARDSON, a citizen of the United States, residing at Newark, county of Essex, State of New Jersey, have invented a certain new and useful 5 Design for a Carving-Fork, fully described and represented in the following specification and the accompanying drawings, forming a part of the same.

10 My invention relates to a design for a carving-fork having tapering tines.

In the drawings illustrating the design, Figure 1 is a view of a carving-fork embodying the design and showing the upper side of the 15 tines, and Fig. 2 is a cross-section of the spiral portion of the tines.

20 In my design each tine is formed with a group of spirals A intermediate to the point and shank, and the tine is tapered from such group to the point B and expanded from such group to the shank of the fork, so that

the whole tine is of approximately tapering form.

The tines are of flat rectangular shape in cross-section, as is indicated in Fig. 2, which 25 also shows the spiral form of the tines where twisted.

The leading feature of my design for a carving-fork is the form of the tines having each 30 the group of spirals intermediate to the point and shank, substantially as shown and described.

What I claim is—

35 The design for a carving-fork as herein described and shown.

In testimony whereof I have hereunto set my hand in the presence of two subscribing witnesses.

CHRISTOPHER RICHARDSON.

Witnesses:

L. LEE,
THOMAS S. CRANE.
